(57) **CLAIM**

The ornamental design for an in-pond filter, as shown and described.

DESCRIPTION

FIG. 1 is a perspective view of the in-pond filter according to my new design;

FIG. 2 is a top plan view thereof;

FIG. 3 is a bottom plan view thereof;

FIG. 4 is a front view thereof;

FIG. 5 is a rear view thereof;

FIG. 6 is a first side view thereof;

FIG. 7 is a second side view thereof;

FIG. 8 is a perspective view of an elongate variation of the in-pond filter according to my new design;

FIG. 9 is a top plan view of the variation of FIG. 8;

FIG. 10 is a bottom plan view of the variation of FIG. 8;

FIG. 11 is a front view of the variation of FIG. 8;

FIG. 12 is a rear view of the variation of FIG. 8;

FIG. 13 is a first side view of the variation of FIG. 8;

FIG. 14 is a second side view of the variation of FIG. 8;

FIG. 15 is a perspective view of another elongate variation of the in-pond filter according to my new design;

FIG. 16 is a top plan view of the variation of FIG. 15;

FIG. 17 is a bottom plan view of the variation of FIG. 15;

FIG. 18 is a front view of the variation of FIG. 15;

FIG. 19 is a rear view of the variation of FIG. 15;

FIG. 20 is a first side view of the variation of FIG. 15; and,

FIG. 21 is a second side view of the variation of FIG. 15.

The broken lines are included for the purpose of illustrating portions of the in-pond filter that form no part of the claimed design.
